UNITED STATES PATENT OFFICE

HARVEY E. CRUM, OF SANTA MONICA, CALIFORNIA

ELECTRICIAN'S SAFETY KNIFE

Application filed February 24, 1927. Serial No. 170,669.

This invention relates to knives and more particularly to that class of knives which are adapted for use by electricians and the like for peeling and cleaning insulated electrical conductors.

An object of my invention is to provide an improvement upon the disclosure illustrated in my co-pending application, Serial No. 157,697 filed December 29, 1926.

10 Another object of this invention is to provide a knife in which the metallic blade is completely insulated from the handle, so that the same may be used upon a wire which is charged without danger of transmitting electrical energy from the wire to the human body.

15 A further object of this invention is to provide a knife wherein the actual cutting blade is slidable within the handle and the same when not in use may be withdrawn into the handle, thereby preventing the knife from ripping the clothing of the user, or endangering leather in the tool-box.

20 A still further object of this invention is to provide a knife which may be hung upon the electrician's belt when the blade is concealed within the handle and which may be quickly removed from the belt and the knife blade exposed for use.

25 Yet, a still further object of this invention is to provide an electrician's safety knife wherein means are provided on the same for holding the knife either in retracted or extended position.

30 A still further object of this invention is to provide an electrician's knife which is extremely durable, which is very unlikely to get out of order and which will withstand heavy duty or rough treatment.

35 With the foregoing and other objects in view which will be made manifest in the following detailed description and specifically pointed out in the appended claims, reference is had to the accompanying drawings for an illustrative embodiment of the invention, wherein:

40 Figure 1 is a side elevation of my knife showing the blade exposed and ready for use.

45 Fig. 2 is a sectional view taken substan-

tially along the lines 2—2 of Figure 1 in the direction of the arrows.

50 Fig. 3 is a view in side elevation of a part forming the locking device in the improved knife.

55 Fig. 4 is a top plan view of the same.

Fig. 5 is a perspective view of the knife blade.

60 Fig. 6 is a vertical section taken upon the line 6—6 upon Figure 1, in the direction indicated.

65 Referring to the accompanying drawings wherein similar reference characters designate similar parts throughout, the improved knife consists of a handle made up of two complementary parts 10 and 11 which present a rounded exterior surface having reduced ends which receive surrounding bands 12 and 13 holding the two parts 10 and 11 together. The two parts 10 and 11 which form the handle are formed of thoroughly seasoned wood, pressed fiber or equivalent material which will act as an electric insulator. In the opposed faces of the parts 10 and 11 there are formed grooves 14 and 15 which co-operate to form a slot extending longitudinally through the handle in which a blade 16 is slidable. The knife blade 16 is provided with a cutting edge 17 and a scraping edge 18 on one end and an aperture 19 on the opposite end. This blade is somewhat longer than the handle, and by virtue of the fact that it is slidable in the slot, it may have either end disposed wholly within the handle or projecting therefrom.

70 Figures 1 and 2 illustrate the knife blade having the end provided with the cutting edge projecting from the handle and the end having the aperture 19 disposed wholly within it. By shifting the blade within the slot the end having the cutting edge can be caused to assume a position wholly within the handle, and the end having the aperture 19 projecting from the opposite end of the handle.

75 The lower part 11 of the handle has the groove 15 formed thereon deepened intermediate its ends as indicated at 20 and 21, to receive the ends of a bowed spring 22. Near the center of the part 11 the groove 15 is deepened materially as indicated at 23, into which the cen-

ter of the spring 22 is capable of being depressed. The other part of the handle indicated at 10 has a circular aperture 24 formed therein which is reduced in diameter near the exterior of the handle to form a shoulder 5 which serves as an abutment adapted to be engaged by a flange 26 on a button 27 which fits within the aperture 24. This button is also formed of insulating material and has its top 10 accessible from the exterior of the handle. On the spring 22 at approximately its center, there is fastened a part U-shaped in cross section having a base or foot 28 fastened directly against the top of the spring 22. An upward standing portion 29 extends upwardly from the base 28 at the side edge of the spring and is then bent forwardly as indicated at 30 to provide a portion fitting in a recess on the under side of the button 27. A pair of 15 notches 31 and 32 are formed in one edge of the knife blade 16, which notches are capable of receiving the base or foot 28. On the opposite side of the knife blade there is formed a long notch 33 into which extends the end 20 of a screw 34 which is preferably formed of insulating material so that the screw, by engaging the ends of the notch 33, limits the sliding movement of the blade within the handle. The ends of the spring 22 are provided with wings which are bent upwardly 25 indicated at 35 and toward each other as indicated at 36, to provide loops in the ends of the spring through which the blade slidably extends.

35 The operation of the improved knife blade is as follows:

When it is desired to use the cutting edge 17 or the scraping edge 18, the button 27 is pushed downwardly. By reason of its engagement with the portion 30 of the part fastened to the spring 22, it will move the spring downwardly into the recess 23 and cause the base or foot 28 to pass out of the notch 31. When this is done, the knife blade 40 is free to slide within the handle, and that end having the aperture 19, can be pushed, causing the edged end of the blade to be exposed. On release of the button 27, the spring will urge the button outwardly and 45 carry the base or foot 28 into the notch 32, the base or foot thus serving as a lock locking the blade in this position. When it is desired to discontinue using the knife, the button 27 can be depressed, causing the base 28 to move 50 out of the notch 32 and the blade can be caused to slide backwardly, and on release 55 of the button the base 28 will again enter the notch 31. In this position the edged end of the knife blade is disposed entirely within the handle and the apertured end is projecting therefrom, permitting the knife to be suspended upon an electrician's belt by passing 60 a snap hook or equivalent part on the belt through the aperture 19. The loops provided 65 on the ends of the spring 22 provide good

bearing surfaces for the ends of the knife blade so that the edges of the knife blade will not cut into the wood or other material forming the handle.

From the above described construction it 70 will be appreciated that an improved electrician's knife is provided, wherein there is a slotted handle formed of insulating material in which a blade is slidably, and that either end of the blade is capable of assuming a position within the handle with the other end projecting therefrom. Also, when in either of its extreme positions, the knife blade is locked in that position and can not be moved from that position until the button 75 27 has been depressed sufficiently to move the base 28 out of its notch in the knife blade. This construction prevents an electrician from becoming accidentally cut by the cutting edge 17, and also prevents his becoming 80 injured by the edged end of the blade coming in contact with a charged wire while the knife is suspended from the electrician's belt. It will be noted that all portions on the exterior surface of the handle are electrically 85 insulated from the blade so that the knife can be used for cutting insulation and scraping a charged wire without danger to the person using it.

It will be understood that various changes 90 in the details of construction may be made without departing from the spirit or scope of the invention as defined by the appended claims.

I claim:

1. A knife comprising a slotted handle 100 formed of insulating material, a blade slidably disposed within the slot within the handle, said blade being longer than the handle and being capable of being moved into 105 a position wherein one end is disposed within the handle adjacent its respective end thereof, and the other is projecting therefrom or into another position wherein the first mentioned end is projecting from the handle and the other end is disposed therein adjacent its 110 respective end, a resilient strip disposed within the handle, said strip carrying means adapted to enter notches in the blade and urged into such position by the resilient strip 115 to lock the blade in either position, and means for depressing the resilient strip causing said means to permit the blade to slide in the handle, said resilient strip providing loops 120 at its ends through which the blade slidably extends.

2. An electrician's knife comprising a slotted handle, a blade slidably disposed within the slot in the handle, resilient means disposed within the handle, adapted to enter notches in the blade and lock the blade in either of its extreme positions, limiting means, carried by the handle and disposed within a long notch in the blade for limiting the sliding movement of the blade in the han- 130

dle, said blade being longer than the handle and adapted to assume either of two extreme positions, in either of which one end of the blade is retracted into the handle and disposed within its respective end thereof,
5 and the other end is projecting therefrom.

3. An electrician's knife comprising a slotted handle, a blade slidable in the slot in the handle, resilient means disposed within the handle on one side of the blade and engageable upon the blade to lock the blade in adjusted position, and a button mounted on the opposite side of the blade from the resilient means, said button being operatively connected to the resilient means to cause it to disengage the blade and permit the blade to slide in the handle.

In testimony whereof I have signed my name to this specification.
